(57) **CLAIM**

The ornamental design for a multi-functional safe-touching tool, as shown and described.

DESCRIPTION

FIG. 1 is a front-top-left perspective view of a multi-functional safe-touching tool showing my design;

FIG. 2 is a rear-top-right perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken line showing of a bottle opener in FIGS. 1 through 7 is for the purpose of illustrating an environmental structure and forms no part of the claimed design.
